UNITED STATES PATENT OFFICE.

GEORGE CHILSON PHILLIPS, OF PROVIDENCE, RHODE ISLAND.

WATER-CLOSET-TANK FLUSHING APPARATUS.

SPECIFICATION forming part of Letters Patent No. 364,289, dated June 7, 1887.

Application filed April 6, 1887. Serial No. 233,885. (No model.)

To all whom it may concern:

Be it known that I, GEORGE CHILSON PHILLIPS, of the city and county of Providence, of the State of Rhode Island, have invented a new and useful Improvement in Water-Closet-Tank Flushing Apparatus; and I do hereby declare the same to be described in the following specification, and represented in the accompanying drawings, of which—

Figure 1 is a vertical section, and Fig. 2 a horizontal section, of an apparatus involving my invention, the nature of which is defined in the claims hereinafter presented.

In the drawings, A denotes the valve, and B the seat thereof, of the educt or water-closet tank, while C is the usual overflow-pipe of the tank, such pipe being screwed into an educt, a, leading into the valve-seat case b, as shown.

Extending from the side of the educt a is a short tubular projection, c, into which there is screwed a cylindrical tube, D, which is open at its lower and is closed at its upper end, except in having an opening, d, through it, and a valve, e, to such opening, such valve being 25 to open upward.

Encompassing and fitting on the tube D is another tube or barrel, E, which is open at its lower and closed at its upper end. From the tube E an arm, f, extends over and is connected to the valve by a short chain or two links, g, the wire h for raising the valve being connected to such arm. Furthermore, there is encompassing the overflow-pipe an adjustable gage, G, to extend directly over the top of the tube E, such gage sliding freely on the pipe, and being provided with a set-screw, i, for fastening it to the pipe at any desirable altitude thereon. The said gage becomes a stop for regulating the height to which the valve 30 and tube E may be raised. On pulling upward the valve the barrel E will rise with it, and while such barrel is sliding upward on its guide and induction-tube D water will be drawn from the latter upward through the 35 valve-seat and into the said barrel E. In and down along the outer surface of the pipe D there is a groove, k, or instead thereof a flattening of the surface, to enable water during descent of the barrel E to slowly escape there- 40 from between it and the pipe D.

From the above it will be seen that by means of a lifting-pump constructed and applied to the tank-valve, substantially as described, the period of descent of such valve may be determined by the time taken for the 55 water drawn into the pump to escape from its barrel, such lifting-pump having its barrel E so connected with the eduction-valve of the water-closet tank as to rise and fall with such water. The amount of water discharged from 60 the tank during each fall of the valve will depend on the period consumed in the descent of the barrel E. The part D is to open at bottom freely into the tank, so that water can readily flow into such part D.

I do not claim, broadly, the combination of a lifting-pump with the flushing-valve of a water-closet, such pump being to regulate the closing of such valve.

I claim—

1. The combination, with the water-closet flushing-valve A, of the lifting-pump, substantially as described, arranged wholly aside thereof, the arm f, extending from the barrel of such pump directly over the valve and 75 connected to its operative wire so as to be movable therewith and with such valve, as set forth, the adjustable gage projecting directly over the pump-barrel and applied to the overflow-pipe, such pump being composed 80 of the tube D, the valve and its seat in the upper part thereof, and the barrel E, closed at top and encompassing the tube D, and provided with an educt or means of discharging water from it, (the said barrel,) as explained. 85

2. The combination, with the tank overflow-pipe and the water-closet flushing-valve of such tank, and the lifting-pump, substantially as described, arranged with such valve and connected with its operative wire, 90 as explained, of the adjustable gage extending directly over the pump-barrel and applied to such overflow-pipe, and having means of fixing it (the said gage) in position on such pipe, all being substantially as represented.

GEORGE CHILSON PHILLIPS.
